MERCURY CATHODE DISCHARGE TUBE

Hendrik Lems and Cornelis Bastiaan Los, Eindhoven, Netherlands, assignors to N. V. Philips' Gloeilampenfabrieken, Eindhoven, Netherlands

Application June 26, 1937, Serial No. 150,623
In Germany July 6, 1936

7 Claims. (Cl. 250—27.5)

Our invention relates to mercury-cathode discharge tubes and more particularly to cathode-spot anchoring bodies for such tubes.

Usually such bodies are made of a metal whose surface is capable of being wetted by the cathode mercury, either by amalgamation or due to its cleanliness. If the bodies are made of an oxidizable metal, such as nickel, it is necessary to completely remove by reduction the oxide layer which is always formed during the manufacture of the tube, in order to allow the amalgamation. On the other hand, if the bodies are made of a metal which oxidizes with difficulty, i. e. metals which remain clean and retain their anchoring properties under all conditions and even at high temperatures, it is necessary to use one of the noble metals, which are comparatively expensive. Although it is possible to use only a layer of a noble metal and a core of a cheap metal such as copper, in such cases the layer must be relatively thick in order that it will not be destroyed within a short time by the discharge and uncover the core material which is not adapted to anchor the cathode spot. This latter construction, in addition to being expensive, also entails manufacturing difficulties.

The object of our invention is to overcome the above difficulties and to provide an anchoring spot body which is inexpensive and at the same time meets all operating conditions.

In accordance with the invention, we form the composite anchoring member from a substratum of a metal which has satisfactory anchoring properties but which readily oxidizes at high temperatures, and provide this substratum, prior to the assembling of the tube, with a thin covering or protective layer of a metal which also has satisfactory anchoring properties but which does not oxidize at high temperatures.

More particularly, in one embodiment of our invention we use a core of nickel and provide same with a protective layer of platinum having a thickness of several microns.

The protective or covering layer need have a thickness of only a few microns because it is not intended to remain intact during even normal operation of the finished tube, as the core when uncovered cannot oxidize in the vacuum of the tube and its surface has satisfactory anchoring properties. Thus the anchoring body remains free from oxide during the manufacture of the tube, and after the tube is completed, the loss of the covering layer can no longer affect the anchoring properties of the anchoring body.

In another embodiment of our invention, which

is inexpensive as to manufacture and materials used, we use a core of an inexpensive metal such as copper, and provide same with a relatively thin layer of the oxidizable metal of satisfactory anchoring properties, for instance nickel; this layer being provided with a very thin protective coating of non-oxidizable metal having satisfactory anchoring properties.

In order that the invention may be clearly understood and readily carried into effect, we shall describe the same in more detail with reference to the accompanying drawing, in which:

Figure 1 is a sectionized view of a mercury-cathode rectifier embodying the invention;

Fig. 2 is a sectionized view of an anchoring body according to one embodiment of the invention; and

Fig. 3 is a sectionized view of an anchoring body according to another embodiment of the invention.

The rectifier shown in Figure 1 has an envelope comprising a cup-shaped metal member 1, for instance of chrome iron, and a glass member 2 hermetically fused together at 17. Disposed in the bottom of member 1 is a mercury cathode 3, whereas a main anode 8 is supported from the lower end of a conductor 6 whose upper end is secured to a metal disc 4 hermetically sealed in glass portion 2 and carrying a suitable terminal. Supported from conductor 6 and surrounding anode 8 is a cylindrical screen 11 serving to protect the higher internal surfaces of portion 1 and seal 17 from the detrimental effects of the discharge.

Supported by screen 11, which is preferably of sheet molybdenum, is an insulating tube 20 through the bore of which extends a conductive rod 19 carrying on its lower end an auxiliary anode 9. The anode 9 is adapted to be moved in the direction of the double-headed arrow, and for this purpose the upper end of rod 19 carries a plunger 18 of magnetic material electrically connected through a compression spring 22 to a core 21 of a magnetic material. Core 21 is supported from the lower end of a conductive rod 7 secured to a disc 5 hermetically sealed in glass portion 2. Outside the envelope and surrounding core 21 is coil 10 which serves to raise anode 9 from the surface of the mercury.

Surrounding the metal member 1 is a cooling jacket 12 having an inlet opening 13 and an outlet opening 14, and through which a circulating cooling medium, such as water, is circulated in the direction of the arrows during operation of the rectifier. Jacket 13 is secured to metal

member 1 by a copper bolt 15 secured, for instance by welding, to the bottom of member 1 and serving to supply current to cathode 3.

Secured to the upper surface of the bottom 5 of member 1 is an anchoring body 26, later to be discussed.

Within the bottom of member 1 and extending slightly from the surface of mercury 3 is an annular member 25, for instance of molybdenum, 10 which serves to prevent the cathode spot from disengaging from body 26, for example, due to excessive loads, and reaching the inner wall of member 1 over the surface of mercury 3. For 15 normal loads, however, the cathode spot will form on the line of contact between the mercury cathode 3 and body 26, a line-shaped area of application whose length is proportional to the discharge current.

In accordance with the invention and as is 20 indicated in Figure 2, the anchoring body 26 is formed of a core 27 of a metal of good anchoring properties but which readily oxidizes, and a thin protective layer 28 of a material of good anchoring properties and which does not oxidize. 25 The core 27 may be of a metal such as nickel, or molybdenum, whereas the layer 28 may be of a metal such as platinum, iridium, palladium, or rhodium. As the layer 28 does not serve any function during the operation of the tube, it 30 may be very thin, for instance of the order of a few microns. For example in the case of platinum it may be about 5 microns.

In constructing the tube, core 22 is secured to member 1, for instance by welding or soldering, 35 and the layer 28 is then applied by the well-known electroplating process or by cathode disintegration.

We prefer to make the anchoring body of a 40 nickel core coated with a platinum layer because nickel has the advantage that it amalgamates with mercury when it has a clean surface, and on the other hand is attacked by the mercury and the cathode spot at such a low speed that a completely satisfactory life of the anchoring body and thus of the tube can be obtained.

Because of this low speed of attack it is possible to further reduce manufacturing costs by 45 making the core of any convenient metal, and a thick layer of an oxidizable metal of good anchoring properties which is covered with a thin covering layer of non-oxidizable metal of good anchoring properties.

Such a construction is illustrated by the anchoring body of Figure 3, which comprises a core 29, a layer 30 of the same material as core 27 of Figure 1, and a covering or protective layer 28.

Core 29 is made of an inexpensive metal which can be worked in a satisfactory and simple manner, for instance by drawing or pressing. For 50 this purpose metals such as copper, or aluminium, or alloys having a high percentage of copper may be used; however we prefer to use copper because it has a high heat conductivity. This allows a maximum heat dissipation from the 55 active surface of the anchoring body through the body to the artificial cooling liquid, to thereby maintain the active surface at the proper temperature, essential for satisfactory functioning of the anchoring body.

The thickness of layer 30 depends upon the 70 material used, and in the case of nickel we have

found that a thickness of about 2 mm. gives a sufficiently long life of the anchoring member. Greater thicknesses may even be inadvisable since, particularly when a copper core is used, dissipation of heat is unnecessarily reduced by the poorer heat conductivity of the thicker nickel layer.

While we have described our invention in connection with specific examples and applications, we do not wish to be limited thereto, but desire 10 the appended claims to be construed as broadly as permissible in view of the prior art.

What we claim is:

1. A discharge tube comprising an envelope, an anode, a mercury cathode, and a cathode-spot anchoring body, said body comprising a nickel substratum, and a thin protective layer of platinum.

2. A discharge tube comprising an envelope, an anode, a mercury cathode, and a cathode-spot anchoring body, said body comprising a core of an inexpensive metal, a layer of nickel upon said core and adapted to act as the final anchoring body, and a thin protective layer of platinum upon said nickel layer.

3. A discharge tube comprising an envelope, an anode, a mercury cathode, and a cathode-spot anchoring body, said body comprising a core of an inexpensive metal, a layer of nickel upon said core and having a thickness of about 2 mm., and a thin protective layer of platinum upon said nickel layer.

4. A discharge tube comprising an envelope, an anode, a mercury cathode, and a cathode-spot anchoring body, said body comprising a copper core, a layer of nickel upon said core, and a thin protective layer of platinum upon said nickel layer and having a thickness of the order of a few microns.

5. A discharge tube comprising an envelope 40 having a metal portion, an anode, a mercury cathode within said metal portion, and a cathode-spot anchoring body secured to said metal portion, said body comprising a core of an inexpensive metal of high heat conductivity and 45 having one surface secured to said metal portion, a layer of nickel covering the remaining surfaces of said core, and a thin protective layer of platinum upon said nickel layer.

6. In a mercury-cathode discharge tube, a 50 cathode-spot anchoring member comprising a substratum of a readily-oxidizable metal of good anchoring properties selected from the group consisting of nickel and molybdenum, and a thin protective layer of a non-oxidizable and mercury-resistant metal of good anchoring properties selected from the group consisting of platinum, 55 iridium, palladium and rhodium.

7. In a mercury-cathode discharge tube, a 60 cathode-spot anchoring member comprising a substratum of a readily-oxidizable metal of good anchoring properties selected from the group consisting of nickel and molybdenum, and a thin protective layer of a non-oxidizable and mercury-resistant metal of good anchoring properties selected from the group consisting of platinum, 65 iridium, palladium and rhodium, said layer having a thickness of the order of several microns.
